TIMEPIECE REGULATOR

Ferdinand Fengler, Bristol, Conn., assignor to
 The E. Ingraham Company, Bristol, Conn., a
 corporation of Connecticut

Application May 16, 1946, Serial No. 670,247

1 Claim. (Cl. 58—109)

1

This invention relates to improvements in time instruments and more particularly to improvements in regulators for time instruments.

Heretofore in time instruments of the marine or lever-movement type, in which the regulator is pivotally mounted on the frame of the timepiece by one of the pivot-bearings of the balance-staff, it happens not infrequently that in assembling these elements of the timepiece, the pivot-bearing associated with the regulator is inadvertently screwed or forced down into the movement-plate to an extent such that the frictional engagement between the regulating-lever and the head of the pivot-bearing is so great as to preclude any movement whatsoever of the regulating-lever. Consequently, when an attempt is made to adjust the timepiece by moving the regulating-arm, the latter is bent or otherwise distorted, thereby eliminating this highly essential feature of the timepiece. Attempts have been made in the long history of the time-instrument art to overcome this difficulty as, for example, by introducing a washer between the lever and the head of the pivot-bearing, and while a certain degree of success has been attained, up to the time of the present invention, no completely-satisfactory solution of this problem has been accomplished.

It is, therefore, an object of this invention to provide an improved regulator construction such that the regulator may be adjustably secured to the frame by the regulator-mounting means but without the likelihood of being bound to the frame thereby.

A further object of the invention is to provide the regulator of a timepiece with segregated resilient means adapted to be cooperatively engaged between the frame of the timepiece and the regulator-mounting means, to preclude the latter from binding the regulator fixedly to the frame of the timepiece.

With the above and other objects in view, as will appear to those skilled in the art from the present disclosure, this invention includes all features in the said disclosure which are novel over the prior art and which are not claimed in any separate application.

In the accompanying drawings, in which certain modes of carrying out the present invention are shown for illustrative purposes:

Fig. 1 is a fragmentary plan view of the rear of the frame of a timepiece, including the balance wheel, regulator, and hairspring assembly;

Fig. 2 is a side elevation of the timepiece-frame shown in Fig. 1;

Fig. 3 is a sectional elevation of the frame and balance-wheel structure on line 3—3 of Fig. 2;

2

Fig. 4 is a perspective view of the regulator; Fig. 5 is a perspective view of the pivot-stud; and

Fig. 6 is an elevational view similar to Fig. 2 but showing the improved regulator used with a conventional pivot-bearing screw.

Referring to the drawings, the frame of the timepiece is indicated generally at 10 and comprises front and rear movement-plates 11 and 12 respectively, joined by pillars 13 in a usual and well-known manner. The balance wheel 14 is rigidly secured to a balance-staff 15 which, in turn, is pivotally mounted at its opposite ends in pivot-bearings 16 and 17 of the front and rear movement-plates respectively. In the embodiment shown in Fig. 2, the pivot-bearing 16 of the front movement-plate 11 comprises a conventional pivot-bearing screw having a head 18 and an exteriorly-threaded shank 19, the extremity of which is dished and hardened to provide a bearing-surface. The pivot-bearing 17 of the rear plate 12 is a stud having an enlarged head 20, a neck 21 having a stop-shoulder 22 and a depending shank-portion 23, as shown clearly in Figs. 3 and 5. The extremity of the shank 23 is dished and hardened to provide a bearing-surface for the adjacent end of the balance-staff 15. Referring to Fig. 4, the regulator is indicated generally at 24 and comprises a relatively-thin flat sheet-metal member having a hub-portion 25 substantially circular in shape; and a flat reach or arm 26 formed integrally with the hub-portion of the regulator. The plane which intersects the longitudinal edges of the arm 26 is substantially at right angles to a horizontal plane through the hub-portion of the regulator (see Fig. 3), this substantially-right-angle relationship between the plane of the arm 26 and the plane of the hub-portion 25 being secured by providing a twist 27 in the arm 26 at its junction with the hub 25. The latter is provided with a concentric aperture indicated generally at 28, the diameter of the aperture being relatively large in comparison with the diameter of the hub-portion 25 of the regulator, so as to form a relatively-narrow annular rim 29. Extending inwardly toward the center of the aperture 28 from the rim 29, are a plurality of resilient radially-disposed fingers 30, the latter being joined integrally at their outer ends with the rim 29 of the hub. The inner free ends of the fingers 30 define a substantially-circular concentric central aperture 31, the diameter of which corresponds substantially to the diameter of the neck 21 of the stud 17. As shown in Figs. 3

and 4, the inner free end of each individual re-

silient finger 30 is elevated above the horizontal plane of the hub-portion 25, the elevated ends of the fingers 30 lying in a common horizontal plane substantially parallel to that of the hub-portion 25. Although three radially-disposed resilient fingers 30 are shown in the present embodiment, it will be understood that the number of fingers may be more or less than three, and that an equivalent structure would comprise, for example, a single resilient element extending from one edge of the rim inwardly to the center of the hub, its inner free end being provided with a central aperture to receive the neck 21 of the stud 17. For a structure embodying a relatively-large number of resilient fingers, the hub of the regulator may comprise a central dished surface provided with a central aperture from which a plurality of radial slots run out to the rim of the hub.

Referring to Fig. 4, the outer end of the regulator-arm 26 comprises a substantially-rectangular vane 32 having a V-shaped notch 33 in its outer edge intermediate its upper and lower ends constituting a relief-recess opposite the frame element 34 of the rear movement-plate 12, to enable the regulator-arm 26 to be swung clockwise to an extreme right-hand position, if such an adjustment is necessary. The lower end of the vane 32 is provided with the usual aperture 35 through which passes one of the turns 36 of the hairspring 37 (see Fig. 3) for effecting the adjustment of the balance wheel 14 in the manner well known to the art.

The regulator 24 is adapted to be mounted on the outer face of the rear movement-plate 12 and to be secured thereto by the pivot-bearing-stud 17, the shank 23 of which is adapted to be driven down into an aperture 38 in the rear movement-plate 12. To facilitate and speed up the assembly of the stud 17, balance wheel 14 and regulator 24, the stud is provided with the aforementioned stop-shoulder 22, the diameter of which is greater than that of the aperture 38 in the plate 12, as a consequence of which the shoulder 22 limits the extent to which the stud may be driven into the aperture 38. When assembled on the outer face of the rear movement-plate, the inner free ends of the resilient fingers 30 of the regulator frictionally engage the underside of the enlarged head 20 of the stud 17 to effectively hold the regulator 24 in any adjusted position, the rim 29 of the hub-portion of the regulator bearing squarely against the outer face of the rear movement-plate, as clearly shown in Fig. 3. While it is conceivable that the height of the neck-portion 21 of the stud 17 could be made to equal substantially exactly the thickness of the hub-portion of a conventional regulator so as to preclude the possibility of binding the regulator to the frame when the stud is driven into its assembled position therein, in actual practice this is impracticable not only because of the unwarranted expense which would be involved in machining the studs to within such close tolerances but also because of the occurrence of unpredictable variations in thickness of the stock from which the regulators are made.

The improved regulator of this invention is adapted to compensate for variations which inevitably occur in the thickness of the stock material from which the regulators are made and in the height of the neck-portion of the stud 17. Thus, it will be clear that when the height of the neck-portion 21 of the stud 17 is greater than the thickness of the rim 29 of the regulator, the

elevated inner free ends of the resilient fingers 30 will frictionally engage the underside of the head 20 of the stud 17 so as to compensate for the increased space between the underside of the enlarged head 20 and the rear face of the rear movement-plate 12, to thereby effectively hold the regulator in any predetermined adjusted position thereon. On the other hand, if the height of the neck-portion 21 of the stud is less than the thickness of the rim of the regulator, then the force which would normally act to bind the regulator to the plate will be dissipated, in part, in the distortion of the elevated resilient fingers 30 of the regulator, the fingers 30 being bent downwardly as the stud is driven into place so as to effectively prevent the hub-portion of the regulator from being bound to the rear face of the rear movement-plate by the enlarged head-portion 20 of the stud 17. Moreover, since the surface area presented to the underside of the stud-head by the ends of the segregated independent fingers, is relatively small, frictional engagement of the stud-head 20 with the regulator 24 is minimized, which further precludes any likelihood of the regulator being bound to the rear movement-plate. The inherently-resilient and independently-acting fingers 30 of the regulator thus serve to compensate for slight variations in the thickness of the regulator or in the dimensions of the stud-pivot bearing associated with the regulator, which variations inevitably occur in the mass production of anything but the most costly precision-built articles.

Referring to Fig. 6, the regulator of the present invention is shown associated with a pivot-bearing 39 of the screw-threaded type. Pivot-bearings of this type are not provided with a stop-shoulder or abutment to limit the extent to which the screw may be turned down into a threaded aperture 40 in the rear movement-plate, as a consequence of which the head of the screw is very apt to bind the regulator to the frame. In fact, it has been a characteristic of this construction that an extremely slight turning of the screw-pivot-bearing 39 beyond that required to secure a regulator to the frame for pivotal adjustment thereon, will bind a conventional regulator fixedly to the frame. However, by providing the improved regulator 24 shown in the drawings, the resilient independent fingers 30 are capable of bending downwardly to automatically compensate for a relatively-large number of rotations of the screw beyond the point where the regulator is frictionally held for rotational adjustment on the frame. Any possibility of binding the regulator to the frame is thereby substantially—and to all practicable purposes—eliminated.

The invention may be carried out in other specific ways than those herein set forth without departing from the spirit and essential characteristics of the invention, and the present embodiments are, therefore to be considered in all respects as illustrative and not restrictive, and all changes coming within the meaning and equivalency range of the appended claim are intended to be embraced therein.

I claim:

In a timepiece, the combination including: a frame; a balance-wheel; bearing-studs fixed in said frame for pivotally mounting said balance-wheel therein, one of said bearing-studs having a neck-portion provided at its outer end with a flanged head and at its inner end with a substantially-square shoulder adapted to seat on

said frame and to hold the said flanged head of said neck-portion positively in spaced relationship to said frame; a hairspring connected to said balance-wheel and to said frame for oscillating said balance-wheel; and a hairspring-regulator comprising an arm having an aperture at the outer end thereof to receive an outer convolution of said hairspring, and a hub-portion at the inner end of said arm lying in a plane at substantially right angles to the plane of said arm, said hub-portion having a central aperture to receive the said neck-portion of said one bearing-stud, and a plurality of integral resilient fingers extending radially into said central aperture and spaced circumferentially therearound, said resilient fingers being arranged to yieldingly engage the underside of the flanged head of the said neck-portion of said bearing-stud to thereby hold the said hub-portion of said regulator-arm

in frictional engagement with said frame for rotational adjustment of said arm with respect to the outer convolution of said hairspring.
